(57) **CLAIM**

The ornamental design for a spin scrubber, as shown and described.

DESCRIPTION

FIG. 1 is a perspective view of a spin scrubber showing my new design;

FIG. 2 is another perspective view thereof;

FIG. 3 is a front elevational view thereof;

FIG. 4 is a rear elevational view thereof;

FIG. 5 is a left elevational view thereof;

FIG. 6 is a right side view thereof;

FIG. 7 is a top side view thereof;

FIG. 8 is a bottom plan view thereof;

FIG. 9 is a partial enlarged view of FIG. 1;

FIG. 10 is a partial enlarged view of FIG. 1;

FIG. 11 is a partial enlarged view of FIG. 1;

FIG. 12 is a partial enlarged view of FIG. 2; and,

FIG. 13 is a partial enlarged view of FIG. 2.

The broken lines in the figures are for the purposes of illustrating portions of the spin scrubber, which form no part of the claimed design.
